PAPER FOLDING MACHINE

George Carruthers and Clarence Edgar Ruddell,
Toronto, Ontario, Canada, assignors to Inter-
lake Tissue Mills Co. Limited, Toronto, Ontario,
Canada

Application June 15, 1933, Serial No. 675,975

13 Claims. (Cl. 270—61)

The principal objects of this invention are, to provide a machine for folding sheets of paper and particularly sheets of tissue paper which may have been cut or perforated and are therefore difficult to handle without being damaged.

A further object is to provide a machine of a simple and durable construction which will accomplish the folding of extremely fragile sheets in a rapid and effective manner.

The principal features of the invention consist in the novel construction and arrangement of mechanism whereby the paper sheets are separated from a stack one at a time by a vacuum device and are rolled into tubular form and then flattened and folded transversely.

In the accompanying drawings, Figure 1 is a plan view of the machine showing the rolling folding mechanism in its position of commencement ready to pick a sheet of paper from a stack.

Figure 2 is a side elevational view of the machine as shown in Figure 1.

Figure 3 is a front elevational view.

Figure 4 is an enlarged elevational detail of the transverse folding apparatus.

Figure 5 is an enlarged sectional elevational detail of the means for feeding the paper sheet holder upwardly to maintain it in engagement with the means for picking off the sheets.

Figure 6 is an enlarged longitudinal sectional view of one of the rolling sheet pick up members.

Figure 7 is a much enlarged cross sectional detail of the roller sheet pick up tube.

The machine is herein shown built up in the form of a rectangular frame having the front and rear uprights 1 and 2 respectively.

Bracket members 3 are secured to the top bars 4 at each side of the frame and they are provided with cylindrical bearing portions 5 extending parallel with the sides of the frame in which are slidably mounted the bars 6.

The forward ends of the bars 6 are formed with heads 7 which are rigidly secured to a cross bar 8.

A pair of brackets 9 are mounted on the cross bar 8, one outside of each of the bars 6. These brackets are slidably mounted on the bar and extend angularly downward toward the front of the machine and rotatably support the tubular members 10 which extend inwardly therefrom and which meet in line with the centre line of the machine.

The tubular members 10, shown particularly in detail in Figure 6, are provided with bevelled blocks 11 at the inner ends and have a row of perforations 12 which are arranged slightly to

the rear of the perpendicular line through the axes of the rollers when they are at their rear-most position.

Bracket bearings 13 are mounted on the cross bar 8 supporting the outer ends of the roller members.

Between the brackets 9 and 13 the roller members have mounted thereon and secured thereto the long pinion sleeves 14 which mesh with the toothed racks 15 which are supported on brackets 16 extending from the frame structure.

A pair of arms 17 are rigidly mounted on the upper ends of vertical shafts 18 mounted in bearing brackets secured to the rear uprights 2 of the frame.

Each of these arms is pivotally connected by a member 19 to the slideable member carrying the brackets 9 and 13, the arms 17 being slideable in the pivotal connection.

Arms 20 are rigidly secured to the lower ends of the vertical shafts 18 and extend inwardly toward each other having the intermeshing toothed ends 21 which will cause them to operate in unison.

A rod 22 provided with an adjustable turn buckle 23 is pivotally connected to one of the arms 20 and its other end is connected to the upper end of a bar 24 which is pivotally mounted on a bracket 25 on the base of the frame.

A cam wheel 26 mounted on a shaft 27 extending transversely of the frame is provided with a cam surface to engage a roller 28 mounted on the upright bar 24. The operation of the cam swings the bar 24 on its pivot and it in turn through the rod 22 swings the arms 20 in unison through their intermeshed toothed ends and the shafts 18 swing the arms 17 outwardly to move the tubular members 10 in an outward or axial direction and inwardly to return them.

At the forward side of the frame and secured to the front upright are the bracket extensions 29 of the frame which project forwardly and are connected across the front by the bar 30.

An arm 31 is pivotally mounted at the base of the machine in the bracket 25 and this is operated by a cam 32 mounted on the cam shaft 27 adjacent to the cam 26.

A rod 33 pivotally connected to the upper end of the arm 31 and adjustable by means of a turn buckle 34 is connected to the cross bar 8.

As the arm 31 is swung forwardly on its pivot on the operation of the cam 32 the cross bar 8 is moved forwardly in a horizontal direction, being supported by the bars 6.

The racks 15 which are in constant engage- 55

ment with the pinions 14 on the tubular members 10, rotate the tubes.

Each of the tubular members 10 is connected by a tube 35 at the outer end to the cross bar 8 which is preferably centrally bored and this centrally bored section is connected with a tube 36 leading to a vacuum pump 37.

The suction of the vacuum pump withdrawing the air from the tubular members 10 causes an inflow of air through the row of perforations 12 in said tubes and this has the effect of picking up the top sheet of paper from a stack 38 supported on a platform 39 arranged above the bracket extension 29. This is particularly shown in Figure 7.

When the cam 32 pushes the arm 31 forwardly the cross bar 8 moves horizontally forward and the pinions 14 in contact with the racks 15 are rotated, thus rolling up the paper on the pair of tubular mandrels 10.

Concurrent with the forward movement of the bar 8 the arms 17 are moved outwardly and such movement draws the tubular mandrels 10 endwise apart so that when the carriage formed by the cross bar 8 reaches the outermost position the mandrels are withdrawn to a point close to the end.

A plate 40 rests upon the outer edge portion of the top of the stack of paper sheets and the rotating mandrels 10 roll over this plate on to a transverse table 41.

The table 41 is provided with a centre slot 42 and arranged below the table and either side of the vertical centre line in the width of the table are two pairs of endless belts 43 and 44. These belts travel vertically with the inner surfaces of one pair running in contact with the inner surfaces of the other pair, thus forming a travelling carrier extending vertically downward from the slot in the table.

A bar 45 vertically slidable in the supplementary frame structure supporting the endless belts 43 and 44 has vertically slidable in its upper end a rod 46 on the lower end of which is secured a folding knife 47. This knife when depressed engages the paper roll carried on to the table 41 by the mandrels 10 and bends it inwardly pulling the ends clear of the mandrels and then forcing the rolled paper down into the slot 42, thus flattening the cylindrical paper formation into a flat fold.

The paper when thus forced down through the slot is gripped between the endless belts 43 and 44 and carried on downwardly, being discharged from the outward end into a rack 48 which is carried on the outer end of the frame bracket.

The reciprocating motion of the folding knife 47 is effected by an arm 49 mounted at the forward end on a shaft 50 extending longitudinally of the frame and said shaft has mounted on its rear end an arm 51 which extends downwardly and engages a cam wheel 52 mounted on the shaft 27.

The cam 52 operates periodically throwing the arm 57 outwardly and the arm 49 downwardly, thus pulling down on the vertical bar 45 to bring the folding knife into engagement with the rolled paper on the mandrels.

A bell crank arm 53 is pivotally mounted on the shaft of the lower rollers of the pair of endless belts 43 and the horizontal end thereof is connected to the arm 49 by a link 54. This link connection operates the vertical arm of the bell crank 53 to swing laterally.

An arm 55 similar to the downwardly extending portion of the bell crank arm 53 is pivotally mounted on the shaft of the rollers of the other pair of endless belts 44. The lower ends of these two arms are connected by a bar 56 which holds them in parallel relation.

Attached to the bar 56 are vertical bars 57 arranged above the guide rack 48 which receives the folded papers.

Each time the folding knife operates, the bell crank arm 53 is swung on its pivot and the vertical bars 57 push the folded papers which have been previously deposited in the rack clear of the bottom or discharge end of the belts 43 and 44. The bars 57 are returned prior to 15 the discharging of the paper folded by the downward movement of the knife 47.

For the purpose of packaging the folded papers it is desirable that some intimation be made of regular numbers or groups as they are placed 20 in the rack. A simple form of device for this purpose is shown consisting of a ratchet wheel 58 mounted on a spindle supported on the guide and operated by a ratchet arm 59 connected with the swinging bar 56. Each time the folder operates and the bar 56 swings, the rod 60 swings the ratchet arm and moves the ratchet wheel one notch.

Mounted on the ratchet wheel spindle is a sprocket carrying a looped chain 61 which has 30 a dog block 62 thereon.

An arm 63 pivotally mounted intermediate of its length has an upwardly curved portion which is engaged by the dog block each time it comes around and when the dog block engages the 35 curved end of the arm the other end which rests on the bottom of the paper guide kicks upwardly and lifts the last deposited folded sheet a short distance upwardly. These sheets, say every ten or twelve as may be desired in the pack, enable 40 the ready separation of the folded group of papers into packs of uniform number.

The pairs of folding belts 43 and 44 are constantly operated through a pair of bevelled meshing gears 64 which are driven by a belt 65 45 passing around the pulley 66 from the shaft 27.

It will be appreciated that as the suction rollers which roll up the paper sheets from the top of the stack operate continuously in the same plane it will be necessary to lift the stack 50 periodically as the sheets are removed therefrom.

The platform 39 upon which the paper sheets are piled operates vertically between guides 68, it being supported from the bottom by a bar 69 55 sliding in the bracket 70 secured in the forward portion of the frame.

The bar 69 is provided with rack teeth 71 and meshes with the pinion 72 mounted on a horizontal shaft and a ratchet wheel 73 is secured 60 to said shaft.

A holding dog 74 constantly engages the teeth of the ratchet wheel in spring held mesh therewith.

Secured to the shaft of the pinion 72 is a bell 65 crank arm 75, the horizontal section of which carries a pivotal dog 76 weighted to engage the teeth of the ratchet wheel.

An arm 77 pivotally suspended is adapted to swing into the path of the dog 76 to hold it out 70 of engagement with the ratchet wheel. This arm is connected with a rod 78 pivotally secured to the bottom end of an arm 79 which is rigidly secured to the spindle pivot 80 of the plate 40 which is engaged by the paper stack, the action 75

being that when the paper stack rises under the plate 40 it swings the arm 79 and the rod 78 to move the arm 77 to engage the dog 76 and temporarily prevent the further operation of the ratchet wheel.

The bell crank arm is operated by a rod 81 connected to its upper end, said rod being connected to a crank arm 82 mounted on the shaft 50 so that when the side cam operates the folding knife it concurrently operates the ratchet wheel to lift the stack of paper sheets a slight distance upward. This upward feed of the paper sheets will of course at times overtake the rolling mandrels and when they press upwardly against the plate 40 the arm 77 moves in to arrest the further operation.

The device is extremely effective in operation. An operating motor, not shown, is connected to the pulley 83 of the shaft 83 and this operates the pinion and gear on the shaft 27 operating the several cams.

The small motor mounted on the frame operates the suction pump to create a continuous suction in the tubular mandrels 10 and in the forward movement of the mandrels they first pick up the edge of the paper as described and as illustrated in Figure 7 and then roll it up and by the operation of the cam 32 the arms 17 are swung outwardly withdrawing the tubular mandrels from the rolled tube of paper.

In the return movement the mandrels roll backward over the paper surface coincidently moving inward toward each other, but as the outward edge of the paper is held by the plate 40, no lifting action takes place, but immediately the rollers reach their innermost position they immediately pick up the free edge of the uppermost paper of the stack and the operation is repeated.

Each time the rollers reach the outer limit of their movement the folding knife moves downward cutting in the paper tube and pushing it downwardly between the endless pairs of folder belts and these belts press the paper together folding it into a compact shape in which form it is delivered into the receiving rack 48 and the folded papers are progressively pushed along the rack and every tenth paper is lifted slightly above its adjacent papers to permit of the easy counting of the folded papers when they are removed.

In the event of the paper fouling the paper mechanism the folding knife 47 which is mounted upon the rod 46 moves upwardly in its supporting bracket and carries with it the collar 84 which is rigidly secured thereto. This collar is pivotally connected to a link 85 on the vertically movable bar 45 and when thus operated a rod 87 carried on the outer end of the link 85 engages a tilting arm 88 which is connected with an electric switch 89 rigidly mounted on the frame operating said switch to break the circuit to the motor operating the machine.

The folding knife is normally held downward with the collar 84 resting against its supporting member on the reciprocating bar 45 by a small weight 90 and when the knife is in this position the switch operating rod does not engage the switch in the downward folding movement. A safety device is thus provided which obviates damage to the parts through the clogging of the folding mechanism.

With a machine such as described thin fragile papers, which may be slotted or otherwise cut,

such for instance as sanitary toilet seat covers, are rolled up without danger of the cut portions spreading or overlapping and are finally folded in a compact form.

It will be of course readily appreciated that many of the details of construction of this device may be altered without departing from the spirit of the invention which is to pick up the sheets by suction coincidently rolling them and finally folding same.

What we claim as our invention is:

1. In a paper folding machine, means for supporting a stack of papers to be folded, rotatable forming means operating with a back and forth movement over said stack, drive means operatively associated with said forming means and effecting the positive rotation thereof during reciprocation to effect the positive winding of the outermost paper therearound, and means for folding and flattening the rolled paper.

2. In a paper folding machine, means for supporting a stack of papers to be folded, a roller adapted to pick up the edge of the top sheet of paper and to roll across the stack, rolling said sheet thereon, means for positively rotating said roller in passage over the sheets said roller being axially displaceable in the machine, means for displacing said roller axially outward to withdraw the roller from the rolled sheet of paper, and means for folding and flattening the rolled sheet of paper.

3. In a paper folding machine, means for supporting a stack of papers to be folded, a hollow axially movable roller adapted to roll across the top of said paper stack and having perforations therein, means for creating a suction within said hollow roller to draw the edge of the top paper sheet into contact with the roller, means for progressively withdrawing the roller axially from the rolled sheet during rotation of the roller, and means for folding and flattening the rolled sheet of paper.

4. In a paper folding machine, means for supporting a stack of papers to be folded, a pair of elongated axially separable tubular members arranged in alignment transversely of said paper stack and engaging the top sheet thereof for substantially its entire width, said tubular members having holes therethrough from end to end, means for effecting a suction through said holes to draw the paper edge to said tubular members from corner to corner, means for moving said tubular members in unison over said top sheet, means for imparting a positive rolling movement to said tubular members to roll up the top sheet thereof, means for drawing said tubular members apart within the roll of paper, means for creasing the roll of paper midway of its length between the separated tubular members, and means for flat folding the creased tubular paper.

5. In a paper folding machine, a frame, means mounted on the frame for supporting a stack of papers to be folded, reciprocating means mounted on the frame adapted to pass over said paper stack, a pair of rollers mounted on said reciprocating means and movable outwardly away from each other, means for positively rotating said rollers coincident with the reciprocation of the means carrying same, a suction device connected with each of said rollers, said rollers having holes therein to admit air to the interior and to effect the lifting of the edge of the upper paper sheet from the stack, means for moving said rollers each a uniform distance outwardly coincident with their rolling movement to separate their in-

70

75

- ward ends and means for folding and flattening the rolled sheet of paper.

6. In a paper folding machine, a frame, means mounted on the frame for supporting a stack of papers to be folded, reciprocating means mounted on the frame adapted to pass over said paper stack, a pair of rollers mounted on said reciprocating means and moveable outwardly away from each other, elongated gear pinions secured to the ends of said rollers, gear racks meshing with said pinions and adapted to rotate the rollers coincident with the reciprocating movement, means for lifting the edge of the top sheet of paper to effect the wrapping of same on the rollers, means for withdrawing the rollers endwise from the roll of paper, means for transversely creasing the rolled paper, and means for drawing the paper roll together from the creased fold and forming a flattened folded sheet.

7. In a paper folding machine, a frame, means mounted on the frame for supporting a stack of papers to be folded, reciprocating means mounted on the frame adapted to pass over said paper stack, a pair of rollers mounted on said reciprocating means and moveable outwardly away from each other, means for rotating said rollers coincident with the reciprocation of the means carrying same, a suction device connected with each of said rollers, said rollers having holes therein to admit air to the interior and to effect the lifting of the edge of the upper paper sheet from the stack, a pair of arms pivotally mounted on the frame to swing horizontally and operatively connected with the roller supporting means, means for swinging said arms outwardly during the movement of the reciprocating member in the rolling of the paper sheet to draw the roller members outwardly from the centre of the roll, means for creasing the roll transversely between the separated ends of the rollers, and means for drawing the creased paper roll downwardly to crease it into flat folded form.

8. A device as claimed in claim 7 characterized by having connected to the horizontally swingable arms a pair of inwardly extending arms having intermeshing toothed ends to cause said arms to operate in unison, a cam operating in the frame of said machine, a lever operated by said cam, and a rod connecting said lever with one of the toothed arms to swing said arms on their pivots.

9. A paper folding machine, comprising a frame, a reciprocating member mounted on said frame, a roller member carried by said reciprocating member, a paper carrying platform arranged below said roller member having papers stacked thereon, a paper folding mechanism arranged beyond said paper holding platform, means for automatically raising said paper holding platform, a displaceable member overlying the top edge portion of said stack and adapted to be displaced by the upward pressure of the stack thereagainst as the platform raising means urges the platform and stack upwardly, and means controlled by the displacement of said displaceable member for controlling said automatic raising means.

10. A paper folding machine, comprising a frame, a reciprocating member mounted on said frame, a paper rolling member carried by said reciprocating member, a paper holding platform arranged beneath said paper rolling member, a vertically operating bar supporting said paper holding platform, a pinion supported in mesh with said bar, a ratchet means for operating said pinion to raise said bar, means operating in unison with the reciprocating member for operating said ratchet mechanism, a displaceable member for controlling the movement of said ratchet means, a folding mechanism adapted to fold the paper rolled by the paper rolling member, and a paper holding platform arranged beneath said folding mechanism.

11. In a paper folding machine, a frame, a shaft journaled transversely of said frame, a cam wheel mounted on said shaft, a reciprocating device mounted on said frame, an arm pivotally mounted on the frame and engaging said cam wheel, means for operatively connecting said arm with said reciprocating device, means carried by the reciprocating device for rolling sheets of paper, said means being slidably mounted on either side of said reciprocating means to move outwardly and inwardly thereon, arms pivotally mounted on the frame and operatively connected with said outwardly moveable means on said reciprocating member, a cam wheel mounted on said shaft, an arm pivotally mounted on the frame and operatively engaging said cam wheel, means connecting said latter arm with the aforesaid pivotal arms to operate them in unison, a vertically reciprocating folding member, an arm operatively connected with said folding member, an arm pivotally mounted on the pivotal support of the latter arm, a cam member carried by said shaft adapted to engage the latter arm to raise and lower the folding member, means for holding a stack of paper sheets in position to be picked up one at a time by the reciprocating member and carried thereby to said folding member, and means for pressing the sheets into flat fold form from said folding member.

12. In a paper folding machine, means for supporting a stack of paper sheets to be folded, means for picking said sheets from said stack and rolling them into tubular form, a reciprocating folding member adapted to crease the rolled sheets of paper midway of their length, a pair of endless belts arranged below said folding member, means for receiving the folded sheets delivered from said belts, and means carried by said reciprocating folder for automatically stopping the operation of the machine.

13. A paper folding machine as claimed in claim 12 in which the reciprocating folding member comprises a main operating member having a relatively movable portion normally moving in unison therewith to engage and fold the rolled paper sheet and adapted when meeting abnormal resistance to permit a relative movement of said main operating member, and means controlled by the relative movement of said main operating member and movable paper-engaging portion for controlling the operation of the machine.

GEORGE CARRUTHERS.
CLARENCE EDGAR RUDDELL.
